REGLET

Rolland E. Willis, Los Angeles, Calif., assignor to
Emil Brown, Los Angeles, Calif.

Application October 14, 1938, Serial No. 234,935

10 Claims. (Cl. 108—26)

This invention relates to reglets, for sheet metal counter-flashing adapted to be installed on exterior building surfaces, and for expansion or so called fragile joints between the vertical walls of two adjacent buildings, or a vertical division in a wall of one building.

Counter-flashings and fragile joints of this character are commonly made from sheet metal, the connection between the flashing or the expansion joint and the wall being made by the aid of a reglet, and in such a way that the joint between the elements is water tight. Use is especially made of this kind of construction for roofs, to cover the edges of the roofing material or flashing and prevent ingress of moisture along these edges. Use of this construction is also made to attach the expansile member of the fragile joint to the adjacent walls.

Thus for example, in the case of counter-flashing, a series of layers of roofing felt, metal or other roofing material, covering a flat or sloping roof, may be turned up at one edge against a steep wall, which may be vertical or sloping. Counter-flashing is ordinarily provided to overlie this edge. It is necessary to secure this counter-flashing to the wall in a water tight manner, and this is done by means of a reglet. It is one of the objects of this invention to improve the construction of such reglets.

Walls to which this attachment is necessary are often formed by pouring concrete in forms. It is another object of this invention to make it possible in a simple and effective manner, to support the reglet to be anchored in the wall, on the concrete form, so that the act of pouring the concrete serves at the same time to embed the anchoring elements of the reglet.

By the aid of this invention, it is not necessary to provide recesses in the concrete wall to receive the counter-flashing. Since the reglet is anchored by the process of casting the concrete, the necessity of providing an anchoring recess in the wall, and of pointing up the recess, is obviated. Furthermore, by the use of this invention, it is not necessary to cut the concrete form to receive any portion of the reglet.

Another advantage obtained by the use of this invention is the ability to readily remove and replace the counter-flashing without removing or injuring the reglet.

The reglet as constructed in accordance with this invention, provides a substantially horizontally extending trough into which a projection formed on the counter-flashing may be engaged, for supporting the counter-flashing. The

length of the trough will usually be required to be greater than the available lengths of the sheet metal, necessitating joining the adjacent sections of reglet by splicing. By the aid of the present invention, it is a simple matter to ensure that the seal is maintained when such splicing is necessary.

In the case of an opening of "fragile" joint, a covering is provided for the vertically extending space between closely adjacent walls. This covering may take the form of resilient sheet metal deeply folded in vertical direction so as to be flexible in a horizontal direction. Here a reglet is disposed in each wall adjacent the space, with the trough extending vertically. The metal cover is disposed with its opposite edges in the reglets.

This invention possesses many other advantages, and has other objects which may be made more easily apparent from a consideration of several embodiments of the invention. For this purpose there are shown a few forms in the drawings accompanying and forming part of the present specification. These forms, which illustrate the general principles of the invention, will now be described in detail; but it is to be understood that this detailed description is not to be taken in a limiting sense, since the scope of the invention is best defined by the appended claims.

Referring to the drawings:

Figure 1 is a pictorial view, illustrating an installation of counter-flashing in accordance with the invention;

Fig. 2 is a fragmentary sectional view, illustrating the manner in which the counter-flashing may be placed into cooperative relation with the reglet;

Fig. 3 is a view similar to Fig. 2 but showing one edge of the reglet turned down to form the sealed joint;

Figs. 4 and 5 are fragmentary sectional views illustrating different manners in which the reglet may be supported on the inner surface of the concrete forms in order to cause it to be properly anchored in the cast walls;

Fig. 6 is a horizontal section through an expansion joint;

Fig. 7 is a similar section through another form of expansion joint;

Figs. 8 and 9 are pictorial views showing modified forms of reglets;

Fig. 10 is a section showing a modified form of reglet in place in a wall; and

Fig. 11 shows the completed installation of the reglet of Fig. 10.

Referring to Figs. 1, 2 and 3 of the drawings

there is a cast concrete wall 1 shown as extending vertically, for example, above a flat roof or the like. Lying adjacent the wall 1 there is shown a plurality of layers of waterproof material 2, such as roofing felt or the like, forming a flashing. Such material may be utilized to overlie a roof surface or other exterior surface that is intended to be protected. Where the upper edge 3 extends along the wall 1, there is an opportunity for moisture to flow downwardly between the wall 1 and the material 2. It is for this purpose that some form of counter-flashing is required to overlie the edge 3, and to protect the seam against moisture.

15 Any counter-flashing thus utilized must be secured to the wall 1 in a water tight manner. For this purpose, use is made of a reglet 4, shown in greater detail in Figs. 2, 3, 4 and 5. This reglet includes an anchoring part 5 by the aid of which 20 it may be anchored into the wall 1. It is made of relatively thin, ductile material, such as sheet copper or galvanized iron, capable of being readily folded over to form spaced upper and lower folds. The doubled over folds are slightly spaced 25 apart and have an upwardly extending loop 6. This loop prevents moisture working along the top of the upper fold from getting into the wall and also serves to anchor the reglet in the wall. The strip of material forming the reglet 4 may 30 extend in a substantially horizontal direction, as indicated in Fig. 1, to correspond to standard sheet lengths.

The edge of the lower fold of the doubled over strip extends downwardly and is doubled on itself 35 to form a narrow trough or hook 7. It is within this trough or hook that the counter-flashing 8 is suspended, as by a downwardly turned lip 10 which hooks over the edge of the trough 7. The counter-flashing 8 then extends downwardly and 40 covers the top edge 3 of the material 2, as clearly illustrated in Figs. 1, 2 and 3.

The counter-flashing elements 8 are usually required to cover a length greater than the standard lengths in which they come. In Fig. 1 the 45 counter-flashings 8 and 9 are shown as in overlapped relation. The upper hook forming the depending lip 10 of counter-flashing 8 is telescoped within the corresponding upper hook formed at the top of the counter-flashing 9. The 50 length of the overlap which may vary is indicated between the lines 11 and 12 of Fig. 1. In order that the narrow trough 9 be not required to accommodate more than one thickness of metal, the lip 10 may be cut away over portions of the 55 overlapping area of the counter-flashings 8 and 9. This is indicated by the sloping surfaces 13 and 14, defining respectively the top portions of the overlapping parts of counter-flashings 8 and 9. This allows free lateral movement of the counter- 60 flashing due to expansion and contraction and prevents damage to the counter-flashing.

The upper portion of the doubled over reglet extends upwardly as indicated by the upwardly extending flange 15 (Fig. 2). This flange 15 is 65 provided with a doubled over hook portion 16. However, as soon as the lip 10 of the counter-flashing is accommodated in trough 7, the flange 4 may be bent downwardly to overlie the top edge 70 of the counter-flashing. This bent over position of the flange 15 is illustrated in Fig. 3. This portion effectively sheds moisture and prevents any foreign matter from dropping into the trough 7. The hook portion 16 is merely for the purpose of stiffening flange 15, so that it lays flat on the 75 finished job. Although the arrangement in Fig.

3 is shown as not compressed along the seam formed between the counter-flashing 8 and the reglet, in actual practice it may be advisable to compress all of the layers of metal upon each other, to form a metal seam.

The slight spacing between the upper and lower portions of the doubled over anchor serves a further useful function. Where there are two reglets required to be placed in abutting relation, as shown in Fig. 1, the abutting joint should be 10 protected so as to prevent moisture from passing between them. Such a joint is illustrated by the line 17 in Fig. 1. In order to protect this abutting joint, a sheet metal member 18 is disposed between the upper and lower portions of 15 the folded over anchoring member. It is then folded over to cover the joint between the abutting troughs 7. The upper flanges 15 may be turned over this overlapping member 18. Any moisture or other foreign matter that may pass 20 between the abutting flanges 15 is diverted by the member 18 away from the corresponding abutting portions of the trough 7. Both the joint between the reglets, and between the counter-flashings, may expand if conditions are such as to 25 cause it.

It will be apparent that should it be desirable to remove the counter-flashing incident to roof repairs or for any other reason, this may be readily done by bending flange 15 (Fig. 3) upwardly 30 toward its original position. This will permit the hook on counterflashing 8 to be lifted out of trough 7, and the counterflashing removed. No damage is done to the reglet, which, after replacement of the counterflashing, may have flange 15 35 bent downwardly again, when the installation will be the same as when new.

One of the advantages of the form of reglet illustrated resides in the facility with which it may be imbedded in the concrete wall. This is done without providing any deep recesses in the mold form or the wall 1. Thus in Fig. 5 the wood form 19 for the cast wall 1 is illustrated as having an inner mold surface 20. The reglet 4, which is intended to be imbedded in the wall, is shown 40 as disposed on this surface 20, and held in place as by nails 21 extending into the form 19 and having their heads engaging the trough 7 and the flange 15. Since these elements 7 and 15 form 45 rather narrow structures, the recesses formed in the wall are comparatively shallow. Such a recess 22 is illustrated in Figs. 1, 2 and 3.

It is possible to attach the reglet 4 in other ways to the mold form. Thus, in Fig. 4, instead of utilizing nails along the upwardly and downwardly turned edge of the reglet, binding wire 23 may be utilized. This binding wire simply encompasses the reglet and has ends passing through appropriately formed apertures in the wood form 24. The free ends may be twisted together as indicated at 25, for holding the upwardly and downwardly extended edges of the reglet against the mold surface 26 until the wall has been cast.

It will be apparent that no cutting or other modification of the form is required incident to the installation of the reglet in the finished wall. The reglet is merely secured to the inside of the form in the proper position so that it is cast in the wall. When the form is stripped, the reglet 65 remains in the wall.

If it is desired to plaster the wall, a layer of plastic 27 may be applied, as shown in Fig. 3, the upper portion of recess 22 serving to anchor the bottom edge of the plastic.

In case a receiving edge, or ground, to plaster against is required, the modified design of reglet shown in Figs. 10 and 11 may be used. Fig. 10 shows the reglet 30 as cast in a wall 31, the reglet being in its original shape. It will be plain that this type of reglet may be attached to the form in the same manner as the first type. The reglet is similar to the first type including a folded anchoring part 32 terminating in an upwardly directed loop 33, the lower fold terminating in a hook or trough 34. The upwardly extending portion 36 of the upper fold 35 however is longer and starts farther back on the fold 35 extending upwardly at a lesser angle. Thus a larger pocket 15 is formed in the wall to receive the plaster. Portion 36 has a doubled over return portion 37 with downward extension 38 terminating in a hook 39. The counter-flashing 8 is hooked into trough 34 as in the first case, and portion 36 is bent downwardly until it is approximately parallel to fold 32, a metal strip 40 indicated by dotted lines in Fig. 10 being used to force extension 39 over the top of the flashing. The part of portion 36 extending beyond the wall forming 25 a ground for the plaster layer 41, as shown in Fig. 11.

It is not necessary that the reglet have the upturned loop along its inner edge to secure it in the wall. Thus, in Fig. 8, the reglet has the folded portion 43 terminating in the upward extension 44 and trough 45, as before. However, the upturned loop is omitted, the folded portion 43 being provided with holes 46 at intervals. When the wall is cast, concrete enters these holes, 35 and forms an anchor when it sets.

Other methods of anchoring the reglet may be used. Thus, in Fig. 9, the inner edge of reglet 47 is deformed, as by crimps 48, to provide an anchor in the concrete.

40 In Fig. 6, an expansion or fragile joint between two adjacent walls 50 and 51 is shown. Reglets 52 and 53, which may be any of the described types, are set in the walls. A convoluted strip of metal 54 has its edges folded to form 45 hooks 55 and 56, which are inserted in pockets 57 and 58 of the reglets. The other leg of the reglet is then bent over to close the joint.

In Fig. 7 the wall 60 does not adjoin the corner of wall 61; thus the hooks 62 and 63 of the convoluted strip 64 are formed at right angles to each. The arrangement of the reglets will be readily apparent.

What is claimed is:

1. In combination with a wall, a flashing 55 against the wall and a counter-flashing covering the joint between the flashing and the wall, the counter-flashing having a folded top edge forming a downwardly pointing trough, means adapted to be anchored to the wall and having a downward extension carrying an upwardly directed trough adapted to receive the trough on the counter-flashing, whereby said means supports the counter-flashing, said means also having another extension adapted to overlie the trough, said 60 means, together with its extensions and trough, extending substantially the full length of the counterflashing, said flange and said extension lying initially in substantially the same plane, whereby the device may be superimposed on the 65 inside surface of a mold form optionally at any angle from vertical to horizontal and without cutting the form, or laid up in a brick wall.

2. A device of the character described, including means forming an anchoring portion adapted 70 to secure the device in a wall and whereby the

device is self anchoring, a narrow trough formed on an extension of the anchoring portion adapted to receive a counter-flashing or an expansion joint covering and to form a water tight joint therewith, said trough being so formed as to permit removal and replacement of said counter-flashing or said covering, and a flange on the anchoring portion adapted to overlay the trough and to form a ground for a plastic layer on the wall, said means, together with its trough, extension and flange, extending substantially the full length of the counterflashing, said flange and said extension lying initially in substantially the same plane, whereby the device may be superimposed on the inside surface of a mold form 10 optionally at any angle from vertical to horizontal and without cutting the form, or laid up in a brick wall. 15

3. In a device of the character described, a strip of thin ductile material doubled upon itself to form a body portion adapted to be embedded in a wall, the upper portion of the body having an upwardly directed continuation, the lower portion of the body having a downwardly directed continuation, the lower continuation having a trough substantially in the plane of the wall adapted for connection with a counterflashing, the free edge of the upper continuation lying substantially in the plane of the lower continuation. 20

4. In a device of the character described, a strip of thin ductile material doubled upon itself to form a body portion adapted to be embedded in a wall, the upper portion of the body having an upwardly directed continuation, the lower portion of the body having a downwardly directed continuation, the lower continuation having a trough substantially in the plane of the wall and on the outer side of said continuation, said trough being adapted for connection with a counterflashing, the free edge of the upper continuation lying substantially in the plane of the lower continuation, said upper continuation being adapted to be bent downwardly to overlie the connection between the counter-flashing and the lower continuation. 25

5. In a device of the character described, a strip of thin ductile material doubled upon itself to form a body portion adapted to be embedded in a wall, the upper portion of the body having an upwardly directed continuation, the lower portion of the body having a downwardly directed continuation, the lower continuation having a trough substantially in the plane of the wall and on the outer side of said continuation, said trough being adapted for connection with a counterflashing, the free edge of the upper continuation lying substantially in the plane of the lower continuation, said upper continuation being adapted to be bent downwardly to overlie the connection between the counter-flashing and the lower continuation, and a strip of metal adapted to be disposed between the doubled over portions to overlie the adjacent edges of adjoining devices, and having an extension adapted to conform with said bent upper continuation. 30

6. In a device of the character described, a strip of thin ductile material doubled upon itself to form a body portion adapted to be embedded in a wall, the upper portion of the body having an upwardly directed continuation, the lower portion of the body having a downwardly directed continuation, the lower continuation having an upwardly directed trough along its free edge and on the outside of the continuation, the free edge 35

of the upper continuation lying substantially in the plane of the lower continuation, said upper and lower portions each extending substantially the full length of the body portion, the upper portion being adapted to be bent downwardly to overlie the trough.

7. In a device of the character described, a strip of thin ductile material doubled upon itself to form a body portion adapted to be embedded in a wall, the upper portion of the body having an upwardly directed continuation, the lower portion of the body having a downwardly directed continuation, the lower continuation having a trough substantially in the plane of the wall and on the outer side of said continuation, said trough being adapted for connection with a counterflashing, the free edge of the upper continuation lying substantially in the plane of the lower continuation, said upper continuation being adapted to be bent downwardly to overlie the connection between the counterflashing and the lower continuation, and to be bent upward subsequently to substantially its original position whereby the counterflashing may be disconnected from the lower continuation.

8. In a device of the character described, a strip of thin ductile material doubled upon itself to form a body portion adapted to be embedded in a wall, the upper portion of the body having an upwardly directed continuation, the lower portion of the body having a downwardly directed continuation, the lower continuation having a trough substantially in the plane of the wall and on the outer side of said continuation, said trough

being adapted for connection with a counterflashing, the free edge of the upper continuation lying substantially in the plane of the lower continuation, said upper continuation being adapted to be bent downwardly to overlie the connection between the counterflashing and the lower continuation, said upper continuation being of such length that when it overlies the trough, it projects from the wall to form a ground for plastic coat on the wall.

9. In a device of the character described, a doubled over sheet forming a wall anchoring portion, both layers of the sheet having aligned apertures therethrough to provide for anchoring the sheet in a wall, one of said layers extending beyond the wall to form an upwardly and outwardly directed trough adapted to receive an edge of the counterflashing, for there attaching the continuation to the counterflashing without the necessity of extending the counterflashing between the layers, the other of said layers being adapted to be bent to overlie the joint between the trough and the counterflashing.

10. A reglet comprising a section of sheet metal bent to provide adjacent center portions connected by an upwardly bent lip, one of the center portions being bent upwardly to provide an upper form-engaging portion, the other center portion being bent downwardly, outwardly, then upwardly to provide a lower form-engaging portion spaced from the upper form-engaging portion behind which there is a trough to receive a portion of the counterflashing.

ROLLAND E. WILLIS.
